United States Patent Office.

DANIEL KELLER, OF BALTIMORE, MARYLAND.

Letters Patent No. 85,936, dated January 19, 1869.

DREDGE-CHUCK.

The Schedule referred to in these Letters Patent and making part of the same.

To all whom it may concern:

Be it known that I, DANIEL KELLER, of the city and county of Baltimore, in the State of Maryland, have invented a new and improved Dredge-Chuck; and I do hereby declare that the following is a full, clear, and exact description thereof, reference being had to the accompanying drawings, making a part of this specification, in which—

Figure 1 is a perspective view of the improved dredge-chuck, representing the drag-rope in the position it would occupy while dragging for oysters.

Figure 2 is a side elevation of the chuck, showing the rope in nearly a perpendicular position, as it would appear when in the act of hauling in the load.

Similar letters of reference indicate corresponding parts in both figures.

This invention relates to a new and useful improvement on dredge-chucks, which are applied to the sides of oyster-boats, and designed to hold the rope, to which the drag-net or dredge is attached, in a proper position while gathering a load, and also prevent the chafing of the vessel while hauling in a load.

Hitherto a long roller has been used, over which the dredge-rope passed, and over which it was drawn in and payed out.

Another plan consisted in applying a chuck-block and swivel-pulley at one end of a roller, over which pulley the dredge-rope was passed while gathering a load.

Both of these plans were found objectionable on account of the rapid wearing away of the chuck-block, and also the dredge-rope.

The nature of my invention consists in the application of one or more grooved and tapering rollers to the outer face of the chuck-block, and in so arranging such rollers that the dredge-rope shall not be allowed contact with the surface of the said block, but shall work freely, and with comparatively little friction upon the rollers, as will be hereinafter explained.

To enable others skilled in the art to understand my invention, I will describe its construction and operation.

In the accompanying drawings—

A represents the side of a vessel.

B, the chuck-block, which is secured, in a rigid manner, to the side of the vessel, so that it extends a short distance above the guard thereof, and inclines toward the bow, as shown in figs. 1 and 2.

C is a roller, which is supported at one end in a bearing formed in the chuck-block B, and at the other end

in a bearing rising from the top edge of the vessel's guard.

To this chuck-block B, I apply one or more rollers, each one of which has a central concave portion, g, terminated by cones g' g', which rollers are inserted partly into recesses formed in the outer face of the block B, and provided with bearings, d d, at their extremities, which bearings keep the rollers in their places, and allow them to turn freely about their axes.

I prefer to use three rollers, E E' F, arranged substantially as described, in the face of the block B, so that about one-half of the diameter of each roller will project beyond the face of this block.

The two rollers E E' receive the rope D upon their faces during the operation of gathering a load, when said rope will be in about the position shown in fig. 1, and the lowermost roller F receives the rope D during the act of drawing in a load, and after the rope leaves the rollers E E', just before it falls to a perpendicular position with respect to the vessel, as shown in fig. 2.

The rope D passes off over the roller C, and sometimes will assume such an angle around the chuck-block B that it is found desirable to carve away the edges of this block, opposite the rollers thereon, as shown at a, b, and c.

From this description of my improved dredge-chuck, it will be seen that the rope D will not be in contact with rolling or anti-friction surfaces during the operation of gathering a load, as well as when drawing in the load; consequently, neither the said block nor the rope will be rapidly worn away.

If the rollers E, E', or F, should become much worn after long use, the same can be readily removed, and others substituted in their place.

Having described my invention,

What I claim as new, and desire to secure by Letters Patent, is—

1. A dredge-chuck, B, having one or more grooved and tapering rollers inserted into its outer face, substantially as described.

2. An anti-friction dredge-chuck, B, having its outer face scored, and provided with rollers or rolling-surfaces, arranged substantially as and for the purposes described.

3. The combination of rollers C and E E' with a dredge-chuck, substantially as described.

DANIEL KELLER.
